DESIGN FOR A HAND DRILL UNIT

Paul Hellman, Los Angeles, Calif., assignor to
Globe Products Manufacturing Company, Los
Angeles, Calif., a corporation of California

Application September 21, 1942, Serial No. 108,286

Term of patent 14 years

To all whom it may concern:

Be it known that I, Paul Hellman, a citizen
of the United States and a resident of the city
of Los Angeles, county of Los Angeles, State
of California, have invented a new, original, and
ornamental Design for a Hand Drill Unit, of
which the following is a specification, reference
being had to the annexed drawing, forming a
part thereof:

Fig. 1 is a perspective view of a hand drill
unit, showing my new design;

Fig. 2 is a front view, somewhat in perspective;

Fig. 3 is a back view; and

Fig. 4 is a top plan view thereof.

I claim:

The ornamental design for a hand drill unit,
substantially as shown.

PAUL HELLMAN.
